UNITED STATES PATENT OFFICE.

BERNARD F. CONKLE AND JAMES T. HALL, OF JUNCTION CITY, OHIO.

WEEDING APPARATUS.

SPECIFICATION forming part of Letters Patent No. 730,095, dated June 2, 1903.

Application filed June 21, 1902. Serial No. 112,639. (No model.)

To all whom it may concern:

Be it known that we, BERNARD F. CONKLE and JAMES T. HALL, citizens of the United States, residing at Junction City, in the county of Perry and State of Ohio, have made certain new and useful Improvements in Weeding Apparatus, of which the following is a specification.

Our invention is an improved weeding apparatus for use on railroad-tracks; and the invention consists in certain novel constructions and combinations of parts, as will be hereinafter described and claimed.

In the drawings, Figure 1 is a top plan view of our implement removed from the car. Fig. 2 is a front elevation of a weeder in place on a hand-car. Fig. 3 is a detail section on about line 3 3 of Fig. 1. Fig. 4 is a detail section on about line 4 4 of Fig. 1. Fig. 5 is a detail perspective view of the front portion of the weeding apparatus. Fig. 6 is a detail sectional view on about line 6 6 of Fig. 2. Fig. 7 is a detail view illustrating the shoe or runner on the inner section of the lateral weeding-frame. Fig. 8 is a detail sectional view on about line 8 8 of Fig. 1. Fig. 9 is a detail perspective view of the rear portion of one of the side weeder-sections, and Fig. 10 is a perspective view of a portion of one of the rear scrapers.

In carrying out our invention we provide a main frame for application to the bed of an ordinary hand-car. The main frame may include, as shown, front and rear cross-beams A and A' and longitudinal beams B and B' and be suitably bolted at C or otherwise secured rigidly upon the bed of the hand-car C'. The rear beam A' extends, preferably, slightly beyond the side beams B and B', its extensions a' being for the purpose of supporting the rear weeder-sections, which operate over the ties at the outer sides of the track or outside the rails of the track, as will be understood from Figs. 1 and 2. These rear weeder-sections are three in number, the middle section D being supported at d pivotally in connection with the rear ends of the beams B and B' and the outer sections D' being pivoted at d' in connection with blocks a² on the rear sides of the extensions a' of the beam A'. The rear weeder-sections comprise frames pivoted at their front ends in connection with

the main frame and having at their rear ends cross-bars upon which bear the weights E, whose rods E' connect at their front ends with the beam A', so the weights proper can rest directly upon the cross-bars at the rear ends of the sections D and D' to exert tension thereon, as will be understood from Figs. 1 and 3. The weeder-blades F are secured adjustably at F' to the curved spring-arms F², whose upper ends are secured at F³ to the rear cross-bars of the pivoted frames, so the tension exerted by the weights E on said frames will be transmitted yieldingly to the weeder-blades F to permit the same to operate as may be desired. It will be noticed the middle section D is wider than the outer sections D', and we employ two weeder-blades F on the middle section, the rods of said blades being connected by a tie-bar f, as shown in Fig. 1. It will be noticed the blades F extend transversely to the track and operate to remove the weeds between the rails and the outer ends of the ties. By our invention we also seek to provide means whereby to remove the weeds from the portion of the track lying outside the ties and usually sloping down to the ditch running alongside the track. To this end we provide devices supported by the main frame and arranged laterally thereto and to the track and adjustable, as presently described, so they may conform and be adjusted to the inclination or width of the portion of the track which it is desired to weed. We also provide means whereby the side drag on such lateral devices will be exerted upon the rail rather than upon the truck or hand-car, so there will be no danger of the latter being pulled off the track in the operation of the invention. These lateral devices are preferably connected detachably with the main frame, as will more fully appear hereinafter. The main frame is provided at its front and rear ends with depending bars G and G', which are provided on their outer sides with the cleats g, open at the top and receiving the longitudinal side bar H, which fits in the said cleats at its ends and is preferably tenoned at such ends to provide the shoulders h, which engage with the depending bars G and G' and hold the bar H from longitudinal movement in the cleats g. We also provide the front bar G on its rear side with a laterally-

opening socket or box G^2 , in which is fitted the inner tenoned end I' of the front bar I of the lateral weeding-frame. This bar I is thus detachably connected at its inner end with 5 the bar G , and a strut-rod I^2 connects the outer end of the bar I with the bar H , near the rear end of the latter, and braces the bar I as desired. The bar I^2 may be hooked, bolted, or otherwise detachably connected at its end i , 10 as shown in Figs. 1 and 5, so it can be readily connected and disconnected whenever desired. The front frame of the lateral weeder includes this bar I , which may be termed the "top" bar, a lower bar J , which is pivoted 15 horizontally at its inner end J' in a box K' on the under side of the intermediate bar K , and the bar K , which is pivoted at K^2 at its inner end vertically in connection with the top bar I , near the inner end of the latter. 20 This permits the outer end of the bar K to swing forwardly and the outer end of the bar J to adjust up and down. This vertical adjustment of the outer end of the bar J is guided by an upright loop L , fixed at its lower 25 end to the bar J and sliding at its upper end over the outer end of the bar K , and the forward adjustment of the bar K is regulated by means of a loop or clevis M , secured at its rear end to the outer end of the bar I , 30 fitted over the bar K and having a series of bolt-holes which may be entered by the bolt M' in order to secure the bar K in any desired adjustment. The operation of this construction will be best understood on reference to Fig. 1 of the drawings. The vertical adjustment of the outer end of the bar J is to permit the lateral frame to adjust itself to different inclinations alongside the rails, while the adjustment of the bar K to the 40 front and rear is to vary the angle of the weeder-blades of the lateral portion of the apparatus and also to permit the narrowing and widening of the lateral portion of the device as may be desired.

45 At the outer end of the bar J , which is the drag-bar of the lateral portion of the weeder, we arrange the supporting-wheel N , which may be adjusted on its connection with the outer end of the lower bar J so it will always 50 run parallel with the rails on which the wheels of the hand-car operate. This wheel N runs along the ditch-line of the track and has a cutter-blade N' , which marks the line of the ditch, as will be understood from Figs. 1 55 and 5 of the drawings. In connecting the wheel N adjustably with the outer end of the bar J we prefer to pivot the axle of said wheel N at N^2 and to provide the axle near its inner end with a slot N^3 , in which operates the bolt 60 N^4 , as will be understood from Figs. 4 and 5 of the drawings.

The bar J supports the drag-bars O , which are pivoted at their front ends at O' to the bar J , extend thence parallel to the rail, and 65 are pivoted near their rear ends at O^2 to the top bar I' of the scraper-frame P , (see Fig. 9,) such scraper-frame having depending side

bars P^2 , to which the scrapers P^3 are adjustably connected at P^4 , as shown in Fig. 9. The drag-bars O extend at O^3 in rear of the scraper-frame and have depending portions slotted at O^4 for the adjustable connection therewith of the axle-bars O^5 of the gage-wheels O^6 . (See Fig. 7.) By these means the gage-wheels O^6 may be set up or down to regulate 70 the depth of cut of the blades P^3 . We provide two pairs of drag-bars O , such bars being tied together by the rod Q and the inner bar being tied to the side bar H by a rod Q' , as shown in Fig. 1. In connection with the bars 80 O we provide in close proximity to the inner side of the lateral weeder-frame a drag-bar R , pivoted at its front end at R' to the bar J , connected near its rear end with the bar H by a spring R^3 , and bifurcated at its rear end, 85 providing the arms R^4 , which support a scraper-frame and gage-rollers similar to those carried by the bars O . It will be noticed that the bars O operate somewhat after the fashion of parallel-rulers, and by setting 90 the outer end of the bar J farther to the front the scrapers P^3 will be inclined rearwardly toward their inner ends in such manner as to scrape the weeds and gravel upwardly rather than down to the ditch and 95 also to operate with a shearing action upon the weeds. The loop-guide L , it will be noticed, permits the lower bar J to rise and fall, whereby it may conform to the inclination alongside the track.

100 The front depending bar G has connected with it the wheel or roller T , which operates upon the inner side of the outer rail, as shown in Fig. 2, and is journaled to the inner end of a bar T' , whose outer end is connected adjustably at T^2 with the bar G , so the wheel or roller T can be adjusted to bear properly against the inner side of the rail in such manner as to prevent the weeding apparatus from pulling the hand-car off the track. It 110 may be preferred to provide the inner section R of the lateral weeding-frame with a shoe or runner U near its rear end, which may bear against the outer ends of the ties and hold the section R against the tension of the 115 spring R^3 , so the scraper of the said section will operate close to the outer end of the ties in the operation of the apparatus.

Having thus described our invention, what we claim as new, and desire to secure by Letters Patent, is—

1. In a weeder for railroad-tracks, a lateral weeding-frame comprising an upper bar, an intermediate bar below the upper bar, and pivoted at its inner end to the upper bar, 125 whereby it may swing forwardly from the upper bar, and a lower bar pivoted at its inner end in connection with the intermediate bar, whereby it may rise and fall at its outer end combined with the weeder devices and 130 the means for guiding the up-and-down movement of the outer end of the lower bar, means for securing the intermediate bar in different adjustment, and the weeding devices proper

having drag connections with the lower bar, substantially as set forth.

2. In a weeder for railroad-tracks, the combination of a main frame, the rear weeding-sections connected with the main frame, the lateral weeding-frame arranged at one side of the main frame and comprising the upper bar, the lower vertically-adjustable bar and the intermediate bar swinging forward and back with respect to the upper bar, and the upper bar and the drag-bars pivoted at their front ends to the lower bar, and the scrapers and their frames, the latter being pivoted to the drag-bars near the rear ends of the latter, whereby the latter operate after the fashion of parallel-rulers, substantially as set forth.

3. The combination in a weeder for railroad-tracks, of the main frame adapted to be supported on a hand-car, a brace-wheel connected with the main frame and arranged to run on the inner side of the outer rail of the track, and the lateral weeding-frame connected with the main frame at one side of the latter, substantially as set forth.

4. In a weeder for railroad-tracks, the combination of a main frame adapted to be secured upon a hand-car, and weeder-frames at the rear end of said main frame and comprising frames pivoted at their front ends in connection with the main frame having cross-bars at their rear ends, weeder-blades provided with curved supporting-rods connected with said cross-bars, and the weights carried by the main frame and operating upon the cross-bars of the pivoted yielding frame, substantially as and for the purpose set forth.

5. In a weeding apparatus for railroad-tracks, a main frame adapted to be supported upon a hand-car, and provided at its rear end with pivoted weeding-frames arranged to operate upon the track, substantially as set forth.

6. The combination in a weeding apparatus for railroad-tracks, of a main frame adapted to be supported and secured upon a hand-car, and weeding-frames jointed at their front ends to the main frame, and provided at their opposite ends with blades to operate upon the track, substantially as set forth.

7. The combination in a weeder, substantially as described, of the main frame, the weeder devices connected with the rear end of the main frame and comprising frames pivoted at their front ends to the main frame and provided at their rear swinging ends with spring-rods and weeder-blades carried thereby, and tension devices operating upon the rear swinging ends of the said frames, substantially as set forth.

8. In a weeding apparatus for railroad-tracks, a main frame adapted to be supported upon the hand-car and provided at its rear end with transversely-extending weeding-blades yieldingly connected with the main frame, substantially as set forth.

9. The combination in a weeder for railroad-tracks, of the main frame adapted to be sup-

ported on a hand-car and provided at one side with the upwardly-opening cleats, and adjacent thereto with the laterally-opening socket, 70 the lateral weeding-frame having a top bar fitting at its inner end in said socket, an intermediate bar pivoted vertically near its inner end to said top bar, and a lower bar pivoted horizontally at its inner end in connection with the intermediate bar, and having the drag-bars and the weeding device connected therewith, the longitudinal side bar supported in the cleats on the main frame, and connections between the drag weeding-frames and the said side bar, substantially as set forth.

10. The combination in a weeder for railroad-tracks, of the main frame, the lateral weeding-frame having a front frame connected with the main frame, and weeding devices proper connected by drag-bars with said front frame and provided at the outer end of the frame with a guide-wheel, and with means for adjustably supporting the same, substantially as set forth.

11. The combination in a weeder substantially as described, of the pair of drag-bars, the scraper and the scraper-frame to which said drag-bars are separately pivoted, substantially as set forth.

12. In a weeding apparatus for railroad-tracks, the combination of the main frame, the lateral weeding-frame jointed at its inner end whereby its outer end may be adjusted forward and back, and the drag-bars provided at their rear ends with the scrapers, and pivoted at their front ends in connection with the front frame and operating after the fashion of parallel-rulers, substantially as set forth.

13. The combination of the main frame, the lateral weeding-frame comprising the top bar, the intermediate bar pivoted vertically below the top bar, the keeper loop or box connected with the top bar and within which the intermediate bar may be adjusted, the lower bar pivoted horizontally at its inner end in connection with the intermediate bar, whereby it may rise and fall at its outer end, means for guiding the vertical movement of the outer end of the lower bar, and the weeder proper connected with the lower bar, substantially as set forth.

14. The combination in a weeder for railroad-tracks, of the main frame, the lateral weeding-frame having a front portion which may be adjusted forward at its outer end, the drag-bars carrying the weeder proper and connected with said front portion, and the gage-wheel carried at the outer end of the said portion and adjustable in connection therewith, substantially as set forth.
